UNITED STATES PATENT OFFICE.

CLACIE E. CORSNITZ, OF HALIFAX, PENNSYLVANIA.

MACHINE FOR REMOVING AND APPLYING CROSS CHAINS.

Application filed March 17, 1925. Serial No. 16,251.

To all whom it may concern:

Be it known that I, CLACIE E. CORSNITZ, a citizen of the United States, residing at Halifax, in the county of Dauphin and State 5 of Pennsylvania, have invented certain new and useful Improvements in Machines for Removing and Applying Cross Chains, of which the following is a specification, reference being had to the accompanying drawings.

This invention relates to an apparatus for removing and replacing cross chains of automobile anti-skid chains and more particularly to a device having means for opening or closing the end links of the cross chains to thereby remove or apply them to side chains of the anti-skidding device.

An important object of the invention is to provide a device of this character which 20 may be very readily and cheaply produced, which will be durable and efficient in service and a general improvement in the art.

A further object of the invention is to provide a device of this character embodying a foot operated reciprocable member which coacts with a pair of anvils, one of which is employed with the reciprocable member to open the link and the other of which is employed with the reciprocable 30 member to close the link.

A further object of the invention is to provide a construction of this character in which one of the anvils affords a means for supporting the other of the anvils and additionally a means for supporting the anti-skid chain upon which the work is being done.

A still further object of the invention is to provide a device of this character of such 40 structure that the hands of the operator are left free to guide the links of the chains to the anvils during the operation of opening or closing the links.

These and other objects I attain by the 45 construction shown in the accompanying drawings, wherein for the purpose of illustration is shown a preferred embodiment of my invention and wherein:—

Figure 1 is a perspective view of a cross 50 chain removing and applying device constructed in accordance with my invention;

Figure 2 is a side elevation thereof;

Figure 3 is a vertical sectional view 55 through the upper end thereof;

Figure 4 is a perspective of the rear of the table removed; and

Figure 5 is a detailed perspective view showing the manner of associating a link to be removed with the anvil 15 and extension 20.

Referring now more particularly to the drawings, the numeral 10 indicates a vertical standard adapted to be supported with its lower end 11 resting upon the floor or other suitable case. Secured to the upper outer 60 face of the standard is a table 12 which is horizontally extending and which has a vertically disposed flange 13 which is bolted or otherwise secured to the standard, as at 14. The table is of greater width than the standard and at the projection at one side, the flange 13 has bolted thereto an anvil 15, the construction of which will hereinafter more 65 fully appear.

That face of the table 12 opposing the 70 standard is formed in opposition to the standard with a notch 16. Depending from the outer or front wall of this slot is a flange 17 paralleling the opposed face of the standard. Between this flange and the 75 standard and between the opposed faces of the sections of the flange 13 is disposed for vertical reciprocation a slide 18 having its upper and lower ends projecting above and below the table. This slide has a horizontal 80 extension at its upper end, indicated at 19, opposing the table and moving toward the table as the slide is moved downwardly. At its upper end, it is also provided with a gooseneck extension 20, the end of which 85 overlies and opposes the upper surface of the anvil 15 in such relation that the inner face of the extension and the outer face of the anvil 15 are arranged in the same plane. The neck 20 and anvil 15 have oppositely 90 beveled faces 21 and 22 forming upon this extension and upon the anvil pointed outer ends 23 and 24. Both the extension 20 and anvil 15 are knife-edged by beveling what 95 is the outer face thereof when the anvil and the extension are arranged in side to side relation as in Figure 2, these beveled faces being indicated at 25 and 26 respectively.

The lower end of the standard is provided 100 with a pair of bearings 27 preferably arranged upon the rear face of the standard, these bearings supporting a shaft 28 extending through a notch 29 formed in the lower 105 end of the standard. Mounted upon the shaft is a pedal lever 30 having a foot 110 treadle 31. A rigid link 32 is engaged at its lower end with the lever 30 at a point

adjacent the front face of the standard and at its upper end with the slide 18. Secured to the treadle lever is a spring 33 normally maintaining the treadle and slide in elevated 5 position.

In the use of the device for removing cross chains, the end link 34 of the cross chain which, as is well known to those familiar with the art, has an eye 35 clamped about 10 the link of the side chain, is so placed upon the anvil 15 that the point 22 of this anvil enters the eye and this eye is vertically arranged. The treadle 31 is then operated to cause the slide to move downwardly and the 15 point 23 of the extension 20 to likewise engage against the eye 35. Continued pressure will cause these two points to pass through the eye spreading the same sufficiently to permit the cross chain link to be 20 disengaged from the side chain. When it is desired to secure the cross chain link to the side chain, the side chain is arranged beneath the horizontal extension 19 and the cross link engaged therewith. The slide 18 25 is then moved downwardly and the extension 19 engages the free ends 36 of the eye and forces them downwardly until the link is firmly engaged with the side chain and unremovable therefrom. During either of 30 these operations, the skid chain is supported from the table 12 and the hands of the operator, which are not required in either operation to manipulate the machine, may be employed for steadyng and guiding this 35 chain.

Since the structure hereinbefore set forth is obviously capable of a considerable range of change and modification without materially departing from the spirit of my invention, I do not limit myself to such specific structure except as hereinafter claimed. 40

I claim:—

1. In a device for removing and applying the cross chains of automobile skid chains, a vertical standard, a table secured to the 45 standard at the upper end thereof and combining with the vertical standard to provide a vertically disposed guide-way, a slide vertically reciprocable within the guide-way, a spring for retaining the slide in elevated position, a foot lever for shifting the slide downwardly, an anvil having a point for engagement in the eye of a chain link carried by the table, a goose-neck carried by the slide and extending over the anvil for engagement with the link to force it against the pointed edge of the anvil as the slide is moved downwardly, and an angular portion carried by said slide overlying the table and adapted to coact with the table to 50 compress therebetween the ends of an open link to thereby close the link.

2. In apparatus for removing and applying the cross chains of automobile skid chains, a vertical standard, a table secured to the standard at the upper end thereof and having a notch opposing the standard, the forward edge of the notch having a flange opposing the standard and combining with the standard to provide a slide guide, a slide 65 vertically reciprocable within the guide, means for vertically reciprocating the slide, said slide having at its upper end an integral angular extension overlying the table and adapted to coact with the table to compress therebetween the ends of an open link to close the same, said slide having a further integral goose-neck extension having a pointed extremity and a pointed anvil carried by the table and with which the goose-neck coacts to open an engaged link. 70

In testimony whereof I hereunto affix my signature.

CLACIE E. CORSNITZ.
